UNITED STATES PATENT OFFICE

92,872

DESIGN FOR A COMBINED SALT AND PEPPER SHAKER

Ewald Abbe, Medford, Minn.

Application May 7, 1934, Serial No. 51,707

Term of patent 7 years

To all whom it may concern:

Be it known that EWALD ABBE, a citizen of the United States of America, residing at Medford, in the county of Steele and State of Minnesota, has invented a new, original, and ornamental Design for a Combined Salt and Pepper Shaker, of which the following is a specification; reference being had to the accompanying drawing, forming part thereof.

I claim:

The ornamental design for a combined salt and pepper shaker, as shown.

In testimony whereof I affix my signature.

EWALD ABBE.
